CALCULATED FRAMING AND FOLDING RULE

David J. Butler, McKeesport, Pa.

Application February 13, 1951, Serial No. 210,719

4 Claims. (Cl. 33—105)

1

My invention relates broadly to folding rules and more particularly to a construction and arrangement of a folding rule which is provided with graduations thereon for quickly marking rafters, beams, risers, treads, etc. for facilitating cutting with minimum expenditure of time.

One of the objects of my invention is to provide a construction of precalculated foldable rule which may be conveniently carried by carpenters on a building job and folded to a triangular position from available specifications on the rise per foot required in any building condition to quickly provide means for marking rafters, beams, risers, treads, etc. for facilitating cutting, eliminating the need for making calculations on each building job.

Still another object of my invention is to provide a construction of foldable rule calibrated for the marking of rafters, beams, risers, treads, etc. to enable the proper angular cuts to be made therein from available specifications with respect to the overall rise per foot necessary in any building construction wherein the foldable sections of the rule are provided with perforations and coacting keying members for maintaining the sections of the foldable rule in selected angular positions determined by the rise per foot required for the rafters, beams, risers, treads, etc. in a building structure for enabling markings to be quickly made and the rafters, beams, risers, treads, etc. cut without the expenditure of time in calculating the angularity of such cuts on the building job.

Still another object of my invention is to provide a foldable rule in which the sections thereof may be interlocked in angular positions determined by the angular requirements for the cuts of rafters, beams, risers, treads, etc. according to graduations thereon precalculated according to specifications based on requirements in rise per foot in a building structure in which the sections of the rule are provided with displaceable slide members having angularly latchable guides thereon displaceable from a linear position with respect to the sections of the rule to positions normal thereto and serving as means for aligning the sections of the rule with the peripheries of the rafters, beams, risers, treads, etc. being marked.

Still another object of my invention is to provide a construction of foldable rule in which the sections of the rule carry calibrations thereon determinative of the angularity required for marking rafters, beams, risers, treads, etc. to meet various specification requirements with regard to rise per foot in any building structure and where-

2

in the sections of the rule are conjointly provided with keying pintles and coacting recesses in the sections of the rule together with slideable guides thereon, each of which include guide members latchable in positions either normal to the plane of the sections of the rule or coplanar therewith for facilitating mounting of the rule in a selected triangular lay-out upon the rafters, beams, risers, treads, etc. to be marked.

10 Other and further objects of my invention are to provide a foldable carpenter's rule having calibrations thereon and associated pocket recesses and coacting keying pintles and adjustable angularly displaceable guides for aligning the rule with the sections thereof maintained in selected angular relationship according to the calibrations thereon for facilitating the marking of rafters, beams, risers, treads, etc. as set forth more fully in the specification hereinafter following by reference to the accompanying drawings in which:

Figure 1 is a perspective view of the foldable rule constructed in accordance with my invention and shown in folded position; Fig. 2 shows the application of the rule of my invention for the markings of common rafters, the view showing the position of the sections of the rule for marking both the top and bottom cuts for a common rafter which must meet conditions in a building construction for a six inch rise per foot; Fig. 2a is a fragmentary view of a common rafter which has been marked at both the top and bottom for cutting without expenditure of calculation time on the building job; Fig. 3 shows the application of the foldable rule of my invention for marking the hip cut in the rafter; Fig. 3a is a view illustrating an installation of a rafter cut at both the top and bottom and at the hip according to the markings which have been quickly made by use of the rule of my invention; Fig. 4 is a view showing the application of the foldable rule of my invention for marking a jack rafter side cut; Fig. 5 shows the application of the foldable rule of my invention for laying out stringers for stairways or steps; Fig. 6 shows the application of the foldable rule of my invention for laying out and marking any angle by folding the rule to the second and third joints and holding the end of the rule on the work on degree markings and designations found on the fifth and sixth section of the rule; Fig. 7 shows a section of the foldable rule illustrating more clearly the recesses or perforations provided therein for receiving the keying means carried by the extremities of the end sections of the rule, the said recesses or perforations being located at calculated positions for

enabling the rule to be folded in the required angular relationship for forming the marking required for the rafters in various building construction; Fig. 8 illustrates sections of the foldable rule which carry the adjustable guides thereon with the angularly movable guide pins which are shiftable to positions either at right angles to the plane of the rule or coplanar with the associated section thereof; Fig. 9 is a view illustrating the calibrations which I apply to the sections of a six foot foldable rule for carrying out the rapid markings of rafters, beams, risers, treads, etc. according to my invention; Fig. 10 is a transverse sectional view on line 10—10 of Fig. 9 and showing the keying member provided on each extremity of the end sections of the rule; Fig. 11 is an enlarged view of the adjustable guide carried by certain of the sections of the foldable rule with the guide pin illustrated in coplanar alignment with the section of the rule; Fig. 12 is an end view of the adjustable guide which is applied to the foldable rule and illustrating the guide pin in full line in coplanar alignment with the section of the rule and in dotted line when moved to a position normal to the plane of the section of the rule; Fig. 13 is a fragmentary view of the adjustable guide broken away to show the means for mounting the guide pin in a position in which the guide pin may be latched selectively in coplanar alignment with the section of the foldable rule or shifted to a position extending normal to the plane of the section of the rule, and Fig. 14 illustrates an application of my invention to the backing of a hip rafter in which the folding rule provides proper markings for the required cuts of the hip rafter.

The foldable rule of my invention has been developed to solve a time-consuming problem in the building industry in which carpenters on building jobs must calculate on each job the angular cuts for common rafters, jack rafters, hip and valley rafters, beams, risers, treads, etc. to meet specifications generally given on the basis of rise per foot. The foldable rule of my invention is provided with graduations which have been precalculated for enabling markings to be made for the proper framing of a building structure. The foldable rule of my invention is a two-way rule, one side of which is provided with calculated markings for laying out cuts for roof rafters, beams, risers, treads, etc. The other side of the rule has a six foot measurement graduation thereon accompanied by recesses or perforations designated according to angular degrees. The rule as calculated on both sides is readily useable by carpenters unable to read a conventional framing square. Because the rule of my invention contains precalculated graduations, the laying out and marking of rafters, beams, risers, treads, etc. is rendered easier, faster and simpler than by use of any previous form of scale of which I have knowledge. The foldable rule of my invention calibrated as hereinafter more fully explained has been found highly accurate and convenient in use since angularly movable guides carried by adjustable guides enable the rule to be maintained in position against the rafters, beams, risers, treads, etc. to permit an accurate marking thereof. The foldable construction of the rule enables the rule to be readily carried by the carpenter at all times eliminating the inconvenience of a conventional framing square.

The foldable rule of my invention may be used with less chance of error than has heretofore been encountered when using a conventional

framing square as the cutting lines may be marked on either of the two equal sides of the triangle which is formed by folding the rule. When using a conventional framing square, one particular side must be used in making a marking cut. Moreover the length or short point of the cut can be marked on either edge of the rafter without turning it or moving it in different positions as is the case in using a conventional frame square.

The calibrations on the foldable rule of my invention show the lengths of the rafters, beams, risers, treads, etc. on the respective ends of the rule thus eliminating confusion with other markings on the scales. The rule when folded for the lay-out of risers and treads according to my invention can be held on the exact riser and tread by guide means which may be adjusted to positions adjacent selected calibrations on the scale, thus eliminating the trouble and inconvenience of applying the rule on the same graduations each time the rule is moved. An angle of any degree can be determined or selected for marking on the job in just a few seconds of time.

The foldable rule of my invention employs two independent sets of markings in addition to the conventional measuring scale; that is, markings for common and jack rafters which are designated in black. For marking common and jack rafters, the rule is folded at the end carrying the black calibrations. The markings for hip and valley rafters are designated in red. For marking hip and valley rafters the end of the rule carrying the red calibrations is folded to a position in which markings may be applied directly to the rafters for insuring the correct angular cuts. In the application of the folding rule for the backing of a hip rafter the rule is folded according to the specified rise on the bottom cut and the depth of the equal angle will give the correct amount to be cut off of the plate cut.

Referring particularly to Fig. 1 the calculated framing and folding rule of my invention is shown in perspective as comprising a six foot folding scale including foldable sections foldable into a compact length convenient for carrying onto the job. Certain of the folded sections which I have designated at 1 and 2 are provided with adjustable slides 3 and 4. These adjustable slides are illustrated more clearly in Figs. 11, 12 and 13 and comprise metallic transversely extending strip members which I have designated at 5 embracing the scale 1 and slidably linearly thereof. Each strip member 5 is apertured at one side thereof as designated at 6 in Fig. 13 for the passage of a rod member 7 which carries on one end thereof a flat shoe 8 which is frictionally forced against the edge of the scale 1 by compression coil spring 9 concentrically disposed around rod member 7 and confined against the inside edge wall of the transversely extending strip member 5. The exterior side wall of the transversely extending strip member 5 is provided with a projection 10 thereon. The projection 10 is centrally apertured for the passage of rod member 7 and is provided with semi-cylindrical recesses which extend on axes at right angles to each other, with the intersection of the recesses coincident with the aperture in the projection 10 through which rod member 7 extends. The end of rod member 7 connects with a pintle 11 of cylindrical section and of a length approximately equal to four times the

thickness of the scale with which the transversely extending strip member 5 is associated. The length of the pintle 11 as described is such that the pintle may readily project beyond the surface of the beam or rafter to which the scale is applied and provide engaging means with the edge of the beam or rafter for maintaining the scale in position with respect thereto while effecting measurements and markings as will be hereinafter more fully explained. The semi-cylindrical recesses in the projection 10 are represented at 14 and 15 extending on axes at right angles to each other and forming latching pockets in which the pintle 11 may be seated under action of compression coil spring 9. In Figs. 11, 12 and 13 I have shown the pintle 11 seated in semi-cylindrical recess 15 in alignment with the edge of scale 1 and in Fig. 12 I have shown in dotted line position 11' the location of the pintle when it is desired to maintain the scale 1 in a position adjacent the edge of a beam or rafter. By grasping the pintle 11 and drawing it outwardly against the force of compression coil spring 9 to a position clearing the semi-cylindrical recess 15, the pintle 11 may be oriented to the dotted line position 11' shown in Fig. 12 and released to occupy the semi-cylindrical recess 14 and maintained in the dotted line position 11' for engagement with the edge of a beam or rafter as shown particularly in Fig. 5. Where the scale is used in effecting measurements and markings which do not require the maintenance of certain sections of the scale against the edge of a beam or rafter,

engineer's graduations are set forth more clearly in Fig. 9. The markings include apertures or recesses shown at 19 extending through or into the scale sections in precalculated positions adapted to receive pintles which project from diagonally opposite ends of the extremities of the rule as indicated at 20 and 21 in Fig. 9. The pintles when engaged in a selected aperture or recess 19 in the scale sections serve to maintain the scale in the selected folded position to enable markings to be made for the proper cutting of the rafters, beams, risers, treads, or the backing of a hip rafter. In using the folding rule of my invention there is little chance of error as the cutting line can be marked on either of the two equal sides of a triangle which is formed by folding the rule. When using a carpenter's square, one particular side must be used for marking out. In using the scale of my invention a long or short point of cut can be applied on either edge of a rafter on turning it or moving it in different positions as with a square.

Markings for the lengths of the rafters are applied on the respective ends of the rule as represented at 22 and 23 in Figs. 2-4 and in Fig. 9 thus eliminating confusion with other numbers on the rule. Precalculated measurements are provided on the rule for all of the probable angular rises which will be encountered in conventional building construction; that is, the required angles for each foot of rise for rises of 4"; 6"; 8"; 10"; 12"; 16" and 18". I provide on the scale 24 a table which I have precalculated as follows:

Rise	4 inches	6 inches	8 inches	10 inches	12 inches	16 inches	18 inches
Length of hip and valley rafters in inches to each foot of run.	17.45	18.02	18.78	19.72	20.86	23.84	24.75

The pintle 11 is oriented from a position normal to the plane of the scale section to a position

At the other end of the scale I provide at 25 a precalculated table reading as follows:

Rise	4 inches	6 inches	8 inches	10 inches	12 inches	16 inches	18 inches
Length of common rafters in inches to each foot of run.	12.64	13.41	14.42	15.62	16.97	20.00	21.63
Lengths of shortest jacks in inches spaced on 16" centers.	16.87	17.87	19.25	20.87	22.62	26.87	28.87
Lengths of shortest jacks in inches spaced on 24" centers.	25.25	26.87	28.87	31.25	34.00	40.00	43.25

coplanar with the scale section enabling the scale section to be readily moved over the surface of the beam or rafter with the obstruction due to the otherwise projecting pintles.

The rule for laying out common rafters, jack rafters, hip and valley rafters, beams, risers, treads and for backing of a hip rafter contains in addition to the graduations and markings applicable to the particular use for which the calculated framing and folded rule of my invention has been developed, an engineer's scale containing graduations in hundredths of a foot transposed to inches and fractions of an inch, or vice versa. The scale also includes measurements respecting surfaces, volumes and areas of geometrical figures useful for rapid calculations on the building construction job where the rule of my invention may be used. I have designated these markings at 16 and 17 in Figs. 2 and 9. The scale graduations on one side of the scale have been designated generally at 18. The special calibrations for determining the angular cuts of rafters, beams, risers and treads which are arranged on the side of the rule opposite to the

The rule thus provides for angular markings for all of the conventional rises per foot usually found in building specifications and also provides means for interpolations of any intermediate values.

The rule with the sections thereof folded in triangular relation for laying out rafters, risers and treads and for the backing of a hip rafter is held on the exact riser and tread graduation by the pintles 11 moved to the position 11' illustrated in Fig. 12 and adjusted by the spacial position of the runners or transversely extending strips 5 to locate the scale in position such as represented in Fig. 5 for example. The pintles 11' are frictionally maintained in position under action of compression coil springs 9 are for all practical purposes locked in position so that the rule may be taken off and applied to successive rafters without reassembly each time that a marking and cut is to be made on any job where the rise is uniform for a multiplicity of rafters. The angle of any cut can be determined and made at any time on a building job very quickly as heretofore explained. The markings appli-

cable to the different kinds of rafters are distinguished by color; that is, the markings for common and jack rafters are black and the markings for hip and valley rafters are red and the different ends of the scale are folded accordingly when applying the rule to these different jobs.

In laying out common and jack rafters it will be noted in Fig. 2 that a number of apertures or recesses are provided in the coacting scale sections. These holes or recesses are designated at

26 where the holes or recesses are marked with the letters C-T in black designating "common rafter-top cut" and other apertures or recesses 27 designating C-B in black for "common rafter-bottom cut." Adjacent these letters I have designated by number the rise in inches. For a practical example: To obtain a top cut for a common rafter with a 6 inch rise, simply fold rule at second and fourth joints, then place the pintle 21 attached to end of rule into hole marked "C-T-6"; a triangle with two equal sides is formed. Either side can be used for marking correct rafter cut shown at 28 in Fig. 2a.

For effecting the bottom cut shown on the rafter at 29 in Fig. 2a the rule is applied by folding the scale sections as explained heretofore but with the end of the rule having the pintle 21 inserted in the hole or aperture marked C-B-6 in black. The bottom plate cut for the common rafter is made by holding the rule as thus arranged over the plumb mark which is the same as the top cut. The rule can be moved to give the amount desired for the plate cut.

A short method may be employed for making these markings and cuts by folding the rule for the bottom cut (C. B.). The plumb cut, or top cut, can be made by holding the straight side of rule directly across the piece and marking one side of the angle. With the same folding of the rule, the bottom plate cut can also be made by using it in the same position as Fig. 3; therefore, all cuts can be made by folding the rule one time only. This also applies to hip and valley rafters, except for their side cuts.

Fig. 9 shows the several sections and both ends of rule, one end in black, the other in red giving lengths of common and hip rafters in inches to each foot of run for rise desired.

An example of the application of the rule is as follows: To obtain length of rafter for an 8 foot run with a 6 inch rise, find under 6 inch rise, the dimension 13.41" which is multiplied by 8 giving 107.28" or $107\frac{1}{4}$ " or 8'-11 $\frac{1}{4}$ " for length of rafters. Also, lengths of shortest jack on 16" and 24" centers are given.

For hip and valley rafters which are the same length and get same cuts, and are obtained by folding red end of rule in same manner (second and fourth joints) as in Fig. 3, but the holes are marked in red "H-T," designating hip and valley top cut designated at 33 and "H-B" hip and valley bottom cut designated at 34.

The backing bevel cut is obtained by folding the rule for hip rafter, bottom cut and using angle X in Fig. 3.

I have shown in Fig. 4 the manner of obtaining jack rafter side cuts. For example a jack rafter side cut with an 8" rise is obtained by using same method as in Fig. 3, but with rule folded at first and second joints, instead of second and fourth joints, and pressing pintle 21 into hole marked 8" and marking the edge of either side. Hip and valley side cuts are obtained in the same manner, by using hip and

valley side cut markings in red on opposite end of rule:

Fig. 5 shows a method used for laying out stringers for stairways or steps. For example, to obtain an 8" rise and a 10" tread, use the same end of the rule in the same manner to obtain common rafter top and bottom cuts, by folding rule at second and fourth joints and inserting the pintle (on end of rule) into hole marked

C. T. 12''
C. B.

15 which forms the rule into a right triangle, then fasten the slides 11' on the folded side of the rule to number marked 8" on one side, and to number marked 9" on the other side, then holding slides 11' against the edge of the stringer, cutting marks can be made for risers and treads.

Fig. 6 shows how any angle can be determined or cut, by folding the rule at second and third joints and holding the end of the rule on the degree markings which are designated by red dots 35 found on the fifth and sixth section 2 of the rule.

25 In Fig. 14 I have shown the manner of applying the folding rule in the backing of a hip rafter designated at 29. In this arrangement the folding sections of the rule are moved to positions designated by the specified rise on the bottom cut. The depth of the equal angles are given the correct amount to be cut off of the plate 29 as designated at 30 and 31. The total amount to be cut off of the plate 29 is designated by the area 32 for properly shaping the hip rafter. This is accomplished by latching pintle 20 of the scale into the designated hip rafter aperture or recess in the associated sections of the rule. I have designated in Fig. 14 typical dimensions for a hip rafter and have shown the manner in which rapid cuts of the proper angularity may be effected.

I have found the folding scale of my invention with the special markings thereon highly useful, practical and efficient in effecting proper angular cuts on rafters, beams, risers, treads and in the backing of hip rafters, etc. While I have illustrated the scale of my invention in one of its preferred embodiments and with certain preferred calibrations thereon, I realize that modifications may be made and I desire that it be understood that no limitations upon my invention are intended other than may be imposed by the scope of the appended claims.

What I claim as new and desire to secure by Letters Patent of the United States is as follows:

60 1. A foldable rule comprising a multiplicity of foldable and unfoldable latching linear sections unfoldable to form predetermined polygonal figures having angular sides adapted to be registered with a work surface for marking and cutting the work surface along prescribed linear marks, runners engaged with certain of the sections of the foldable rule, each of said runners including a friction member engageable with the linear side of the section of the rule, a rod member extending from said friction member and projecting through the side of said runner, a pintle carried by the external end of said rod member and means carried by said runner for latching said pintle in either a position extending normal to the plane of the rule or a position aligned with the section of the rule.

2. A foldable rule as set forth in claim 1 in which a coil spring is interposed between said

friction member and the interior of the side of said runner and surrounds said rod member for yieldably maintaining said pintle in a position adjacent the exterior of said runner and shiftable to either of the two positions thereof.

3. A slidable runner for a scale comprising a runner embracing the face and opposite edges of a scale and apertured at one side thereof, a projection carried by the side of said runner adjacent the aperture therein, said projection having semi-cylindrical recesses therein extending linearly on axes substantially normal to each other, a rod member extending through the aperture in the side of said runner and through said projection, a friction shoe carried by one end of said rod member and engageable with the edge of the scale, spring means interposed between the rear face of said friction shoe and the inside of said runner and surrounding said rod member and a pintle carried by the external end of said rod member and adapted to be seated selectively in either of the semi-cylindrical recesses in said projection, said pintle when maintained in the semi-cylindrical recess normal to the plane of said scale projecting beyond opposite faces of the scale for distances sufficient to form a grip with the edge of the work against which the scale is applied, while said pintle when yieldably maintained in the recess aligned with the edge of the scale is coplanar with the plane of the scale.

4. A runner for the sections of a multiple section foldable and unfoldable scale comprising a strip member slidably engageable with the face
